UNITED STATES PATENT OFFICE.

GUY W. RUTLEDGE, OF HURON, SOUTH DAKOTA.

JOURNAL-BOX JACK.

1,385,892.

Specification of Letters Patent. Patented July 26, 1921.

Application filed March 1, 1918. Serial No. 219,897.

To all whom it may concern:

Be it known that I, GUY W. RUTLEDGE, a citizen of the United States, residing at Huron, in the county of Beadle and State 5 of South Dakota, have invented certain new and useful Improvements in Journal-Box Jacks; and I do hereby declare the following to be a full, clear, and exact description of the invention, such as will enable others 10 skilled in the art to which it appertains to make and use the same.

This invention relates to car jacks and the primary object of the invention is the provision of an improved jack for lifting journal 15 boxes, so that the brasses can be readily removed and inserted into the same.

Another object of the invention is the provision of an improved car jack having means for engaging the upper surface of the 20 car wheel, a jack depending from said means, and flexible means depending from the jack for engagement with the journal box so that upon operation of the jack, the journal box will be lifted upwardly and 25 the weight thereof sustained by the car wheel, so that the brassings or bearings can be readily removed or inserted from the journal box.

A further object of the invention is to 30 provide an improved suspension car jack including a supporting member carrying the jack which can be either suspended from the car wheel to lift the journal box upwardly or can be inverted and set upon a platform 35 supported by the car rails for pushing the journal box upward.

A still further object of the invention is to provide an improved journal box jack of the above character which is durable and efficient in use, one that is simple and easy to manufacture, and one that can be placed upon the market at a reasonable cost.

With these and other objects in view the invention consists in the novel construction, 45 arrangement and formation of parts, as will be hereinafter more specifically described, claimed and illustrated in the accompanying drawings, forming a part thereof, in which:

50 Figure 1 is a front elevation of a car wheel showing my improved jack applied thereto, showing the journal box in section.

55 Fig. 2 is a side elevation of the car wheel showing my improved jack applied thereto with parts of the same in section.

Fig. 3 is a view of the improved jack showing the same supported upon a platform, which is adapted to be placed on the railroad rail, and

Fig. 4 is a plan view of the platform for receiving the car jack.

Referring to the drawings in detail, wherein similar reference numerals designate corresponding parts throughout the 65 several views, the numeral 1 generally indicates the improved jack which is adapted to lift a journal box 2 of a car wheel 3 for removing or inserting the brass 4 therefrom.

The improved jack 1 includes a supporting bracket 5, which is adapted to engage and be supported by the car wheel 3, and the same has its under surface at the rear end thereof provided with a transversely extending groove 6 for receiving the flange 7 of the car wheel 3 and for forming a hooked end for engaging the inner side of the wheel. A downwardly extending enlargement 8 is formed on the outer end with a 80 bracket 5 in spaced relation to the hooked end thereof and forms a shoulder 9, which is adapted to engage the outer side of the car wheel 3. The enlargement 8 bearing against the outer side of the car wheel prevents the 85 bracket from sagging, when the journal box 2 is being lifted. A vertical aperture 10 extends through the bracket 5 and the enlargement 8 in which is positioned the lifting screw 11 and the same is supported by 90 and operated by a nut 12, which is positioned in the inwardly extending slot 13, which communicates with the aperture 10.

The lower end of the lifting screw 11 is provided with a head 14, the purpose of 95 which will be hereinafter more fully described. The upper surface of the bracket 5 is provided with a smooth bearing portion 15, the purpose of which will hereinafter more fully appear. Positioned above the 100 head 14 of the lifting screw 11 and on each side thereof is a hook 16 for receiving the free ends of the flexible chain 17, which is adapted to extend around the journal box.

In operation of the improved device, the 105 bracket 5 is placed on top of the car wheel 3 so that the inner end of the same is hooked over the wheel and the flange 7 of the car wheel is placed in the transverse groove 6 and the flexible chain 17 is then positioned 110 around the journal box 2 and its ends are hooked over the hooks 16. Upon rotation

of the operating nut 12, the lifting screw will be forced upwardly carrying the journal box 2 therewith, which will permit easy removal or insertion of the brasses 4 from the journal box.

In some few instances it has been found by practical experience that the suspension bracket 5 cannot be placed over the wheel 3 owing to the fact that the frame of the car is too near the car wheel due to breakage of the body and to provide for this occurrence a flat plate or platform 18 is provided for supporting the jack. The platform consists of a body 19 having inwardly extending spaced arms 20 formed on the end thereof between which is adapted to be positioned the car wheel 3 and the arms have their inner surfaces thereof adjacent to their outer ends provided with grooves 21 for receiving the flange 7 on the car wheel. A centrally disposed inwardly extending tongue 22 is formed on the body intermediate the arms 20 and is arranged to engage the inner surface of the tread of the wheel to prevent displacement of the plate. This plate is positioned on the track with the arms on each side of the wheel as described above and the plain outer surface 15 of the bracket 5 is placed upon the body portion 19 of the platform which projects outwardly from the wheel and track and is positioned below the journal box 2. The chain 17 is unhooked from the hook 16 and the nut 12 rotated for bringing the head 14 under the journal box and upon further rotation of the nut 12 the journal box will be lifted so as to permit the removal of the brasses 4 therefrom.

From the foregoing description taken in connection with the drawings, it can be seen that an improved and simple journal box jack is provided which can be either suspended from the top of the car wheel for lifting the journal box upwardly or can be positioned below the journal box and supported upon a platform supported by the car wheel and track for forcing the journal box upwardly.

In practice, I have found that the form 50 of my invention, illustrated in the accompanying drawings and referred to in the above description, as the preferred embodiment, is the most efficient and practical; yet realizing the conditions concurrent with the 55 adoption of my device will necessarily vary, I desire to emphasize the fact that various minor changes in details of construction, proportion and arrangement of parts may be resorted to, when required without sacrificing any of advantages of my invention as set forth.

What I claim as new is:—

1. A journal box jack comprising a bracket, a lifting member adjustably mounted in the bracket and operably and selectively extensible beyond opposite faces thereof, said bracket being reversible and one of the said faces being engageable with a car wheel and the other face being engageable with a support auxiliary to the car wheel.

2. A journal box jack comprising a bracket provided with an inwardly extending slot at one end, a lifting screw member 65 mounted in said end and crossing the slot, a nut on the screw member in the slot operable to selectively extend the screw member beyond the upper or lower surfaces of the bracket, said bracket being reversible 70 with its lower surface provided with a car wheel-engaging portion and with its upper surface substantially flat in order to rest on a support auxiliary to the car wheel.

3. A support for journal box jacks comprising a substantially flat body with parallel arms extending therefrom and a space intermediate the arms, a flat wheel engaging projection extending into the space and lying in the same plane as the body, and 85 said arms at their inner edge having a notch extending completely therethrough.

In testimony whereof I affix my signature in presence of two witnesses.

GUY W. RUTLEDGE.
